United States Patent Office

Des. 213,827

Patented Apr. 15, 1969

213,827

CHAIR

Alex Strassle, 9533 Kirchberg, Saint Gall, Switzerland

Original design application Aug. 15, 1967, Ser. No. 8,274. Divided and this application May 7, 1968, Ser. No. 11,828

Term of patent 14 years

Int. Cl. D6—01

U.S. Cl. D15—1

Fig. 1

Fig. 2

Fig. 3

Fig. 4

Fig. 5

FIG. 1 is a front elevational view showing my new design;

FIG. 2 is a side elevational view thereof;

FIG. 3 is a rear elevational view thereof;

FIG. 4 is a plan view; and

FIG. 5 is an underside view thereof.

This is a division of my copending application, Ser. No. D, 8,274, filed Aug. 15, 1967.

I claim:

The ornamental design for a chair, substantially as shown.
